US0D1068723S

(12) **United States Design Patent** (10) **Patent No.:** **US D1,068,723 S**
(45) **Date of Patent:** **** Apr. 1, 2025**

(54) **HEADSET**

(71) Applicant: **Apple Inc.**, Cupertino, CA (US)

(72) Inventors: **Robert D. Brunner**, Glen Ellen, CA (US); **Christopher Kuh**, San Francisco, CA (US)

(73) Assignee: **Apple Inc.**, Cupertino, CA (US)

(**) Term: **15 Years**

(21) Appl. No.: **29/954,443**

(22) Filed: **Jul. 26, 2024**

Related U.S. Application Data

(60) Continuation of application No. 29/894,350, filed on Jun. 8, 2023, now Pat. No. Des. 1,037,204, which is a continuation of application No. 29/859,457, filed on Nov. 10, 2022, now Pat. No. Des. 992,528, which is a continuation of application No. 29/823,119, filed on Jan. 14, 2022, now Pat. No. Des. 969,773, which is a continuation of application No. 29/795,780, filed on Jun. 21, 2021, now Pat. No. Des. 941,262, which is a continuation of application No. 29/706,360, filed on Sep. 19, 2019, now Pat. No. Des. 922,978, which is a continuation of application No. 29/642,633, filed on Mar. 30, 2018, now Pat. No. Des. 860,969, which is a continuation of application No. 29/574,209, filed on Aug. 12, 2016, now Pat. No. Des. 814,438, which is a continuation of application No. 29/504,827, filed on Oct. 9, 2014, now Pat. No. Des. 764,435, which is a continuation of application No. 29/464,539, filed on Aug. 18, 2013, now Pat. No. Des. 716,760, which is a division of application No. 29/426,082, filed on Jun. 29, 2012, now Pat. No. Des. 691,112, which is a (Continued)

(57)

CLAIM

The ornamental design for a headset as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a right side view thereof;

FIG. 6 is a left side view thereof; and,

FIG. 7 is a top view thereof.

The broken lines in the figures show portions of the headset that form no part of the claimed design.

1 Claim, 7 Drawing Sheets

Related U.S. Application Data

continuation-in-part of application No. 29/410,585, filed on Jan. 9, 2012, now Pat. No. Des. 698,749.
